UNITED STATES PATENT OFFICE.

WILLIAM GROTH, OF SEATTLE, WASHINGTON, ASSIGNOR OF FIVE-SIXTHS
TO THOMAS S. CONSTANTINE, OF NEW YORK, N. Y.

POSTMARKING AND STAMP-CANCELING MACHINE.

SPECIFICATION forming part of Letters Patent No. 472,497, dated April 5, 1892.

Application filed January 5, 1891. Serial no. 376,732. (No model.)

To all whom it may concern:

Be it known that I, WILLIAM GROTH, a citizen of the United States, residing at Seattle, in the county of King and State of Washington, have invented certain new and useful Improvements in Postmarking and Stamp-Canceling Machines; and I do hereby declare the following to be a full, clear, and exact description of the invention, such as will enable others skilled in the art to which it appertains to make and use the same.

In a patent granted to me January 7, 1890, No. 419,014, for postmarking and stamp-canceling machines I have described, shown, and claimed certain novel parts and combinations of parts wherein a pneumatic device is operated in a way to take up letters from separate packages and carry them by a free over movement to and deposit them by a vertical drop upon an intermittently-moving endless apron at the point where they are to receive the dating and canceling impression. For such operation the organization of the machine, as shown in said patent, embraced, among other things, a series of compartments for containing separate and distinct packages of letters, a stamping and canceling device having its impressing - stamps arranged separately in registering relation to said separate letter-containing compartments, an intermittently-operating pneumatic letter-transferring device having suction-tubes in correlative arrangement and number with the letter-containing compartments and the stamping and canceling devices, and an intermittently-operating endless apron for conveying the letters in separate and distinct parallel lines from the stamping and canceling device. In such organization it will be seen that the capacity of the machine for the needs of the postal service is determined by the number of the stamps and their co-operating devices which may be used. It will also be seen that the operation of the said patented machine requires that all the letter-containing compartments must be kept supplied with letters to be taken up and carried to receive the impression of the stamps in order to prevent inking the apron by the stamps, and that in the event of the non-supply or the giving out of such supply of any one or more of the com-

partments the stamp or stamps registering with such compartment or compartments having no letters would make an impression on and thus deposit ink upon the surface of the apron, inasmuch as all the stamps operate in such patented machine whether there be letters to receive their impression or not. This inking of the apron was found objectionable, because letters which were subsequently deposited upon the inked apron would thereby be smeared with the ink under the action of the stamps.

The object of my present invention is to render it unnecessary to supply all the compartments with letters and to provide for rendering such stamp or stamps of the series as may not be supplied with a letter to receive its impression shunted out as to its stamping function while descending upon the apron, and thus prevent it from being carried in contact with the apron, while at the same time not interfering with the stamping function of the stamps which may be supplied with letters in the operation of the machine or with the operation of the device which carries all the stamps. In effecting these results I provide for shunting or cutting out any one or more of the series of stamps from action during the continuous operation of the machine and of the continuous function of the stamp - operating mechanism, whereby such stamp or stamps as may not be supplied with letters to receive the impressions will be prevented from touching the apron, while the stamp-carrying device is not interrupted in its regular movement toward the apron. For effecting this operation I provide each stamp proper of the series with a rock-shaft crank device, which under the descending movement of the stamp is caused to strike and press hard upon the immovable apron, which, not yielding under such pressure, serves to arrest the descent of the stamp proper, so it cannot come down on the apron when no letter has been placed under the stamp. For this purpose the apron must be at a standstill and the stamp-carrier must fully descend for the proper action of the other stamps, and as the movement of the other apron is not to carry the letters to the stamps it is therefore timed to be without movement while the letters are being stamped

and to move to carry the letters away from the stamps after receiving their impressions. The function of this stamp-shunting cranked device therefore depends solely upon its downward pressure with an abutting action directly upon the apron, so that the latter serves as a fixed base to resist the downward pressure of the cranked device caused by the descent of stamp itself. In this way each stamp is provided with its own shunting device whereby to render it inoperative to prevent the inking of the apron when the latter contains no letter to receive the impression, while the machine in every particular is operating to postmark and to stamp-cancel letters by stamps in which the shunting device is made inoperative. To render this stamp-shunting device inoperative, or, as it were, taken away from the stamp, so as to leave the latter under the free and sole control of the continuous stamp-operating mechanism, I provide each stamp proper of the series with a plunger device and connect it with one of the cranks of said rock-shaft in such a manner as to shunt or turn and hold up the crank, so that it can have no function, and thereby isolate or take away from the stamp the very device which acts to arrest its descent, as stated. This function of the plunger-rod is rendered active by the descending movement of the stamp so as to bring it down under pressure upon the letter to be stamped. In such function of the plunger-rod the letter forms a fixed base to arrest it, and thereby rock the crank-shaft to shunt out of action its crank-arm. The office of this plunger device therefore is not to raise or to prevent its descent, but, deriving its function from the descent of the stamp and by striking upon the letter, serves only and solely to shunt out of action the rock-shaft cranked device. In the co-operation of these two stamped devices it will be seen that they both depend primarily for their function upon the intermittent action of the endless apron to afford an abutting element to resist the downward movements of such devices to render their function operative or inoperative for the purpose stated. To effect this co-operation, therefore, it is essential that the normal positions of the stamps, the normal positions of the stamp cranked device, and the normal positions of the stamp plunger-rod must be out of the path of the movement of the mail-matter—that is to say, above or away from the letter-supporting apron—in order that both of these devices shall be subject to the control of the stamp itself, in order that one of them will be rendered inoperative by the other, to the end and sole purpose of preventing the inking of the apron. To render the plunger-rod of any one of the stamps inoperative, I provide the endless apron with openings, preferably by forming separate aprons for each stamp, so as to leave spaces between them which register with the plunger-rods to allow the latter to plunge or pass down freely below the apron and thereby allow the crank-

arm to descend upon the apron to shunt the stamp out of action when there is no letter to receive its impression. It will therefore be seen that an essential requirement of the action of the stamp and for its non-action, for the action of the stamp crank-rod, and for the action of the stamp plunger-rod and for its non-action is that the movement of the endless apron must be intermittent, that it must be without movement when the impression is made upon the letter, that it must be without movement to render the crank-rod operative to shunt out the action of the stamp when there is no letter in position to receive the impression, and that it must be without movement to render the plunger-rod operative to shunt out of action the crank-rod of the stamp. These provisions and their mode of operation also require that the letter, after being placed to receive the impression of the stamp, must be without movement, at a standstill on its supporting-bed, and that therefore the action or non-action of the stamp is not and cannot be effected by the movement of the letter upon the apron with it or independent of it.

In the accompanying drawings I have illustrated, substantially, my said patented machine, and prefer to use all the features of my present invention and improvements in said organization in total combination, as such reconstructed machine has been found to be effective and not easy to get out of order in the expeditious work required for the postal service.

In the drawings, Figure 1 represents in elevation the left side of a machine for postmarking and canceling letters embracing my invention; Fig. 2, the opposite or right side of the machine. Fig. 3 is a vertical longitudinal section of the machine, showing the pneumatic device in the position it occupies at the moment of dropping a letter in position upon the apron to receive the impression of the stamp and the stamping device in its highest position. Fig. 4 is a similar section of the upper part of the machine, showing the pneumatic device in the position it occupies at the moment of taking up a letter and the stamping device in position to make the impression on a letter. Fig. 5 is a vertical sectional view showing the mechanism for operating the inking-roll and the stamp-carrier. Fig. 6 is a detail top view of the stamp-carrier, showing its connection with the vertical end slides. Fig. 7 is a detail vertical sectional view showing the operating connections of the stamp-carrier. Fig. 8 is a top view of three of the letter-supporting aprons, showing the open spaces between them and the holes in their bed-support to allow the stamp plunger-rod to pass below the apron when its connected stamp is impressing the letter. Fig. 9 is a horizontal section of the same, showing the grooves and apron-ribs for maintaining the separated relation of the aprons. Fig. 10 is a top view of one of the

letter-supplying compartments. Fig. 1^a, Sheet 1, is a detail view of the ratchet device for intermittently operating the endless apron. Fig. 1^b are views of the tappet-shaft crank-pin and its slotted plate connection for operating the letter-supporting followers. Fig. 2^c, Sheet 2, shows the valved air suction and exhaust cylinder in section. Fig. 4^d, Sheet 4, is a vertical sectional detail of the ratchet device for feeding the followers and the letters thereon to the suction take-up tubes. Fig. 4^e is a detail sectional view of the suction take-up tube. Fig. 11, Sheet 7, is a side elevation of one of the stamping devices, showing the stamp-box in partial section and the shunting-plunger down. Fig. 12 is a side elevation of the same, showing the shunting-plunger up. Fig. 13 is a partial horizontal section through the type-wheel of the stamp, showing the manner of adjustably securing it to the stamp-shank. Fig. 14 shows the stamping and impression made of the stamp. Fig. 15 shows in top view the slotted portion of the stamp-head. Fig. 16 is a vertical cross-section of the same on the line x, and Fig. 17 is a similar section on the line y of Fig. 15. Fig. 18 is a front elevation of the stamp, the type-wheel being in face view, and a section of the endless apron and its supporting-bed, showing the shunting device in position to shunt the stamp in its descent out of action. Fig. 19 is a similar view showing the type-wheel raised to clear the stamp-head and in position to change its dates; and Fig. 20 is a rear elevation of the stamp, showing the action of the plunger-rod in shunting out of action the stamp-shunting crank device.

The drawings show parts and devices of the said patented machine in the same relation and which have the same function as in said patented machine, and among which is the row of compartments 1 for supplying the letters in separate and distinct packages, arranged at the front of a suitable frame. At the rear of the frame a similar row of compartments 3 is provided, which register with the front compartments for receiving the letters after having been postmarked and their stamp canceled, while between these parts are arranged endless aprons 4, upon which the letters are deposited by the dropping action of the pneumatic transferring device to receive the impressions of the stamps and delivered into the receiving compartments. These parts are arranged at the top of the frame in such relation that the letters are lifted from the front part, carried to and dropped upon the aprons, and delivered at the rear, as stated. The devices for transferring the letters singly from their supplying-compartments to the endless aprons and also for postmarking and canceling are arranged for operation above the frame, and their operating mechanisms are arranged and disposed at each end of the frame, while the power-shaft 5 is mounted above the front part of the frame.

I will now describe more particularly these separate mechanisms. Each of these letter-supplying compartments is provided with a follower 10, upon which the letters are placed in packages and fed upward, and each follower has a central sustaining-rod 11, which passes through a suitable guide 12 and is raised with an intermittent feed by mechanism shown in Figs. 3 and 4^d and operated from the power-shaft 5 through the action of the tappet rock-shaft 24, whereby the letters of the several packages are fed upward as each top letter is removed from the package by the sucker-tubes. The device for transferring the letters from the supplying-compartments, in connection with this follower-feed, consists of a bar 29, mounted upon crank-arms 28, so as to have a movement in the arc 85 of a circle. This cross-bar carries sucker-tubes 30 on its under side in registering relation to the letter-supplying compartments and the stamps, and they are maintained in vertical position in every part of the circular sweep 90 of the bar by means of supplemental crank-arms 31, which have a parallel relation to the crank-arms 28, as seen in Figs. 3 and 4, whereby the suction-tubes are caused to descend vertically to take up the letters by suction and to hold them and to carry them to the points where they are dropped by releasing the suction upon the aprons. These sucker-tubes are provided with suitable valves 41, which are opened by contact with the letters to be lifted to render the suction active. Suitable air suction and exhaust devices are employed to suck up and hold the letters, so as to close the mouths of the sucker-tubes and to destroy the vacuum in the latter to drop the letters at the desired points upon the aprons. In this way and by the means shown, while all the sucker-tubes are in communication with the suction and exhaust devices, each one is rendered independent of the other by its valve, and is thereby made operative in the compartments which may contain letters.

The letter-supporting endless apron 4 is mounted upon rolls 61, and at a point above the rear roll a cross-bar 62, Figs. 5 and 6, is mounted in the frame and carries the post-marking and canceling stamps, which are placed at distances along the length of said bar corresponding to the positions of the letter-containing compartments, and this bar is operated vertically in guides a, Fig. 6, in the end frames to raise and to depress the stamps in unison with the letter-transferring device and the devices for feeding the letters up in their supply-compartments, as I shall now state.

Referring to Figs. 3 and 4^d, it will be seen that the rock-shaft 24, which operates the letter-supporting followers 10, is provided at its left end with a short crank-arm 44, (see Figs. 1 and 1^b), which stands toward the rear and has a crank-pin 45, which extends beyond the outer side of the end frame and into a slot 46 in a plate 47, mounted upon a bear-

ing, upon which it oscillates at a point above the rock-shaft. This slot 46 is concentric with the bearing of the plate and terminates in a deflected or oblique end 49, so that the 5 crank-pin 45 is rendered inactive by the concentric portion of the slot and is caused to be depressed by the deflected end 49 of said slot, whereby it causes the shaft 24 to be rocked, carrying its tappets 25—one for each follower—
10 inward against the arms 19 of a ratchet device 17 18, and thus release their engagement from the ratchet-wheels 17, the function of which and the toothed wheel 16 is to hold the followers, and thus allow the followers to
15 rise by the action of weights 22 at the moment the transferring device is at the limit of its descent to take the letters up. In order that this movement of the transferring device shall be in unison with the seizing action
20 of the sucker-tubes, I provide the said slotted plate 47 with a short crank-arm 50 at its pivot-bearing, which arm by a pitman 51 connects with the front end of a lever 52, mounted on a bearing of the frame. This end of the lever also connects by the rod 54 with a crank-pin 53 on the face of a gear b, mounted on a stud of the frame. The other end of this lever 52 has a pin 53', which engages a segmental slot 54' in the face of a gear-wheel 55
25 and has an oblique relation to the axis of said gear. Engaging with this gear 55 is a pinion 56 on the end of the crank-arm 28, which carries the cross-bar 29 of the sucker-tubes. As the lever 52 is vibrated the action of its pin 30 53' within the segmental slot 54' of the gear causes the latter to move through a determined portion of a revolution alternately with a movement each way sufficient to give a half-revolution of said crank-pinion 56 and thereby
35 control with precision and exactness the sweep of the transferring device to take up and deposit the letters in position for postmarking and canceling. In this operation the upward movement of the front arm of the lever 52 operates the said gear-slot 54' to effect the frontward sweep of the transferring device, while the downward movement of the said lever operates in the said gear-slot to reverse the gear and effect the rearward sweeping movement of
40 the transferring device. In this movement the gear-slot 54' also serves the purpose of retarding the movement of the transferring device at its taking-up and depositing point, as stated in my said patent. A train of gear (seen in
45 Fig. 1) connects the followers and the letter-transmitting devices with an inking-roll 86, the endless apron 4, and the stamp-carrying device for conjoint operation, as I will now describe.

50 Referring to Fig. 1, b is a gear-wheel, which carries the crank-pin 53, that connects with and operates the tappet-crank shaft 24, and also connects with, and operates the pinions 56, which are on the crank-arms 28, which
55 carry and operate the letter-transferring device. This gear-wheel b engages a gear-wheel c, which latter engages a pinion d on the

power-shaft 5, and by means of the intermediate pinions e and f and a gear-wheel g, which engages a pinion h on the shaft of the inking-cylinder i, the latter is operated from the power-shaft. A pitman-rod 79 connects the gear-wheel c with a lever 80, which connects with and intermittently operates the endless aprons by means of a ratchet device, 75 which I will presently describe.

The train of gear which I have described gives a positive motion to the shaft which carries the inking-roll 89 forward beneath the stamps when the latter are raised, and this 80 movement is effected as follows: The inking-roll shaft 89 is journaled in the lower ends of hanging arms j, which are pivoted on the inner walls of the end frames, so that the said roll is free to be swung backward in contact 85 with the inking-cylinder i and forward under and in contact with the stamps, as I shall presently describe.

The stamps are suitably mounted on and carried by a horizontal cross-bar 62, which is 90 provided at each end with a vertical slide-plate k, adapted to fit and move between the guideways a, secured on the inner walls of the end frames, as seen in Figs. 6 and 7, whereby a true vertical movement is given to 95 the stamps, as I will now state. A rock-shaft l, mounted in the end frames, has an arm 77 thereon, (seen in Fig. 6 and in dotted lines in Fig. 7,) which by means of a crank-pin 76 thereon stands and works in a slot 75 in a 100 plate-bar 73, which is fitted to slide in ways 74 on the outer side of the right end frame. This slide 73 is connected by a rod 72 with a crank-pin 71 on a gear 70, which engages with and is driven by a pinion d' on the power-driven shaft, 105 which has the pinion d on its other end, so that the reciprocating motion thus imparted to the slide is transmitted to the stamp-carrying bar 62, as I will now state. On the rock-shaft l, which is operated by this slotted slide-bar 73, there is an arm m at each end just on the inner side of the end frames, standing inward and connected at their inner ends to the lower ends of links n, each of which is pivoted to the slides k of the said stamp-carrying bar 62, so that the rocking movement of the said shaft l will vibrate the arms m, and thus raise and lower the slides k to operate the stamp-carrying bar in the way stated. 110 Looking at Fig. 2 it will be seen that the slot 75 of the slide-bar 73 is somewhat L-shaped, so as to have the function of a cam, which as the slide is caused to move forward with the crank-pin 76 in the frontward horizontal portion of said slot the rock-shaft l will be without motion and the stamp-carrying bar will be held in elevated position; but the moment the crank-pin 76 enters the rear inclined or cam part of the slot 75 the crank-arm 77 will be depressed and the shaft l rocked, bringing 115 down the stamp-carrying bar to impress the letters. It will be understood that in this position of the stamps and at this instant the transferring device is in position to seize and 120

125 130

take up the letters and is caused to sweep over and to deposit the letters about coincident with the time of the reverse movement of said slotted slide, which causes the return 5 rotation of said rock-shaft *l*, which brings the stamps again to their normal elevated position out of the way of the transferring device. It will also be understood that at the moment of depositing and at the moment of impressing 10 the letters the endless aprons are without movement and that they have a suitable cross-bed support *s* in the line of the action of the stamps. It will also be understood that the letters which have received the action of 15 the stamps are carried rearward by the aprons and delivered into the receiving-compartments 3 in the same arrangement in which they were placed in the supplying-compartments.

20 I have stated that the inking-roll *s* is suspended so as to be swung under and in contact with the stamps, and by referring to Figs. 3 and 4 it will be seen that the inking-cylinder *i* is mounted in the frame at the rear of the inking-roll *s* and that the latter is mounted in spring-sustained bearings or boxes fitted in guides in the lower ends of the suspending-hangers *j*. A horizontal rider or bearer *o* is fixed to each end frame at its inner side, and 25 against the under sides of which the inking-roll rides, and the stamp-carrying bar has at each end a depending rider or bearer *o*², which in the highest position of the stamp-carrying bar are brought in registering relation to the fixed riders, as in Fig. 3, so that 30 the two riders *o* *o*² at each side of the frame form the ways on which the inking-roll is carried under the series of stamps to ink them in a horizontal plane permitted by the yielding of its spring-sustained bearings. The mechanism for operating the inking-roll consists of slotted slides *p*, one fitted in a guide *q*, secured to the inner side of each end frame and connected by a slotted end *q'* with a pin 35 *r* on each of the swinging hangers *j*, the other end of slotted slide *p* being connected by a pin *r'* with a cam-groove *r*² on the face of a gear-wheel *r*³, mounted on a stud at the inner side of each end frame, which engages with a 40 pinion *s* on each end of the shaft of the inking-cylinder *i*, as seen in Fig. 5. The ink cylinder *i* is operated by the pinion *h*, which engages with the train of gear connecting the power-shaft, as seen in Fig. 1; and the movements of the slotted slides *p* of the inking devices are so timed as to carry the inking-roll under and away from the stamps while they are at rest in their highest position. During 45 the movements of the stamps the inking-roll is swung back in contact with the inking-cylinder, which, constantly revolving, rotates the inking-roll to keep it inked. The inking-cylinder is covered with suitable felt for holding the ink, and the inking-roll is provided with 50 separate sleeves covered with felt for inking the stamps, and these felted sleeves are arranged to register with said stamps.

The intermittent movement of the apron may be effected by any suitable means. That shown consists of the power-shaft, connecting-gear *d c*, the rod *79* and the gear *81*, and a ratchet-wheel *82* on the gear *81*, which latter is mounted loosely on a stud, so that a pawl *83* on the arm *80*, engaging said ratchet-wheel *82*, turns the gear *81* intermittently, and this turns the pinion *84* on the roll *61* intermittently, and thus moves the aprons at the time stated. In this arrangement it is necessary to give the proper movement to the aprons that the pawl *83* shall act on the ratchet *82* only as allowed by a shield-plate *t*, arranged to partially cover the teeth of the ratchet, as seen in Fig. 1a.

I will now describe the construction of the stamps and the provisions whereby any one 85 or more of them are shunted out of action without interrupting the action of the others or of the operation of the machine. The stamps are of identical construction, and the stamping part proper is composed of two 90 parts—a horizontal stamp-head *A*, which carries face letters and type, and a vertical wheel *B*, which carries radial type. The stamp-head has engraved on its under face the letters indicating the location or place of mailing and the stamp-canceling lines making the impression, as seen in Fig. 14, and it has two parallel slots, within one of which are fitted type for printing the month and day.

The type *u*, Fig. 16, are of dovetail form and 95 are held in the dovetail seats of the slot by a removable cap-plate *v* to give convenience for removing and for changing them, which can be done quickly by removing the said cap-plate and using a pick in an inclined hole in 105 the upper end of the type, as seen in Figs. 16 and 17. This stamp-head has a central shank *C*, standing at right angles, which has its upper end fitted within a bore of the box *D* and is retained therein by a shoulder *E*, Fig. 11, 110 on its upper end, which shoulder also serves to limit the downward movement of the stamp within its box against the force of a spring *F*, inclosed within said box *D*, and against which spring force the stamping device is permitted to yield in stamping the letters. A 115 side feather *w*, Fig. 20, prevents the turning of the stamp-shank within the box. Within the other head-slot *x* operate the type-arms *G* of disks which indicate the time of the day, 120 and to obtain the proper indication of the division of the time to denote any hour or half-hour I use three independent disks *H*, which I call "time-wheels." These disks are loosely mounted on a stud *I*, which is secured to the 125 side of the stamp-shank *C* between its head *A* and the box *B*, so as to be vertically movable for adjustment thereon. A convenient means for securing this stud *I* to the stamp-shank is shown in Fig. 13, and consists in making a 130 dovetail recess *y* on the inner end of the stud and fitting it over a dovetail rib or projection *y*² on a flat part of the stamp-shank *C* and clamping the said stud to this dovetail rib by

6

a thumb-screw J, passing centrally through a threaded bore in the stud I, so as to bear against the stamp-shank in a recess Z, Figs. 11 and 13, to permit the stud I to be set 5 higher or lower for a purpose which I shall presently state. The time-wheels II are placed side by side on the stud between two disks II², which are fastened to the latter by screws, and the types are formed upon the 10 ends of circumferential radial arms G, of which the outer wheel has twelve, containing numbers from "1" to "12," inclusive, to indicate the hours of the day. The inner wheel has three type-arms bearing the divisions of the 15 day, "A.M.," "P.M.," and "M.," while the intermediate type-wheel has the number "30" to indicate the half-hour. Each of these type-wheels has a recess on its vertical face to receive a pawl h² and a spring h¹, bearing upon the 20 pawl, Fig. 18, while the stud-hub I has twelve circumferential grooves v^2 of V shape, into which the pawl of each type-wheel is held by the spring when the wheel is properly set, as in Fig. 18. This construction allows the type- 25 wheels to be easily and quickly set for use, and when so set, as in Figs. 11, 12, and 18, the type-arms G extend down through the slot x with their type-faces on a level with the engraved letters of the stamp-head, and the stud 30 is clamped to the stamp-shank by the hand-screw, the point of which is conical and enters the lower one of two recesses z in the dovetail rib, as seen in dotted lines in Figs. 11 and 19. To change the type-wheels, the 35 stud I is unclamped and raised so that the hand-screw J will enter the upper recess z to hold the type-wheels up free of the slot x in the stamp-head to allow the wheels to be turned to change the day or the time, or both, 40 as seen in Fig. 19, after which the stud is again set down and clamped to the stamp-shank. This mounting of the type-wheels upon a sliding stud gives the advantage of 45 conveniently handling them to make the required changes and provides a firm fastening to the shank of the stamp to resist the thrust upon the type-arms. The type-wheels are free to be turned upon the stud, and when so turned they are held by the engagement of 50 the spring-pawl h² with the grooves v^2 of the stud-hub. It will be seen that the cap-plate for the stamp-head slots has a slot v^2 , corresponding with the slot or mortise x, through 55 which the type-arms G pass, and the cap-plate may be locked, if desired.

In the machine the stamps are arranged in registering relation to the letter-supplying compartments 1, and as these compartments may all or only some of them be in use in 60 supplying letters at the same time to the transferring device I find it necessary to make the stamp independent in its stamping function of the movement of its carrying-bar, so that, although all the stamps may be operated alike, 65 those having the letters supplied to them will be shunted out of action to prevent such stamps from striking the apron 4 and inking

it. For this purpose I provide the shank of each stamp with a shunting device, as follows: A horizontal bore is made in the shank 70 of each stamp between its stamp-head and the end of its containing-box to receive a rock-shaft K, having on one end a depending crank-arm L, long enough to extend below the stamp-head A, and on the other end a shorter arm 75 L', standing at about right angles and forming a double-cranked rock-shaft.

A bracket M on the stamp-head supports a vertical barrel or tube N at that side of the stamp-shank at which the short crank-arm L' 80 stands, and into this tube a plunger-rod P is fitted and retained by a shoulder P', Fig. 11, which limits its descent at a point below the stamp-head. The upper end of this plunger-rod is connected by a pin p', Figs. 11 and 20, 85 and slot p² with the short crank-arm L', and a spring p³ constantly tends to depress the plunger-rod P, and the spring force so exerted acts through the pin p' and slotted crank-arm L' to maintain the long crank-arm 90 L in a vertical position, as seen in Figs. 11, 18, and 19, so that this long crank-arm L and the plunger-rod P will both stand below the face of the stamp. The barrel or tube N has a slot through which the pin p' of the plunger-rod extends to permit the vertical movement 95 of the plunger-rod to operate the rock-shaft through its slotted arm.

I prefer to provide each stamp with a separate endless apron, so as to place them apart 100 to leave a space 42, Fig. 8, between their edges in registering relation with the plunger-rods, so that the latter will descend without hindrance below the apron when no letter has been supplied to receive the impression of the 105 stamp, as seen in Fig. 18. In this event the crank-arm L will be brought down with the stamp and will strike upon the apron 4, and thus arrest the further descent of the stamp C and prevent it from coming into contact with 110 and inking the apron. In thus arresting the descent of this stamp the stamp-carrier 62, however, is allowed by the spring F in the stamp-box to continue its full downward movement, so as not to interfere with the 115 stamping function of the other stamps to which letters may have been supplied. In this way the crank-arm L serves to shunt the stamp C out of action when it is descending, and in such function of the shunting 120 crank-arm the apron 4 serves as a fixed base or abutment. When, however, a letter is in place to receive the impression of the stamp, this crank-arm L must not be in position to act as a shunt upon the stamp, and for this 125 purpose I provide means whereby this crank-arm is shunted out of action. This is effected by the plunger-rod P, which, descending with the stamp, strikes directly upon the letter Q, which latter thus arrests the further descent 130 of the plunger, (see Fig. 20,) because the letter Q stands as a cover for the opening 4² in the apron 4, while the stamp, continuing to descend, causes the long cranked arm L to be

turned to one side out of the way of the stamp, so that it is free to act, as seen in Figs. 12 and 20. This shunting action of the plunger-rod P is produced by its pin connection p' with the short slotted crank-arm L', which is turned upward, and, rocking the shaft, also turns its long crank-arm L up to raise it above the stamp. As both these shunting devices are carried directly by the stamp, they move with it and are only brought into action by its descent upon the apron in one case and upon the letter in the other case and at a time when both the apron and the letter are without movement. Otherwise both the apron and the letter would be constantly liable to be cut and torn. I provide for holding the separate aprons in parallel relation by means of one or more ribs 4³ fastened on the under side of each apron, and grooving the rolls to receive these ribs, as shown in Figs. 8 and 9. I also provide the cross-bed 85, which supports the aprons under the action of the stamps, with holes 4⁴ "", which register with the spaces 4² between the aprons 4 to permit the plunger-rod P to pass down between the aprons, as seen in Fig. 18.

The supply-compartments 1 being filled with letters and the machine started, the pneumatic device brings its sucker-tubes 30 down upon the letters, which open their valves 41, and are seized and held thereto by suction. Then rising, the device carries the letters over to the rear and drops them upon the endless aprons, as seen in Fig. 3, and instantly returns to repeat the seizing of letters. During this return movement the stamp-carrying bar is in its highest position, as seen in Fig. 5, and the inking-roll 89 is caused to move forward to ink the stamp-faces and to move back out of the way. The stamp-carrying bar 62 at once descends to effect the required impressions of the stamps upon the letters. During the interval between the deposit of the letters and the making of the impressions thereon the endless aprons are at rest. The letters having received the impressions of the stamps, the latter immediately rise and the endless aprons 4 are moved forward to carry the letters to the receiving-compartments.

50 The release or dropping of the letters by the sucker-tubes 30 is effected by the reverse stroke of the piston R of the air-cylinder R² acting to destroy the vacuum in the sucker-tubes, as seen in Figs. 2 and 2^c.

55 The suction device consists of a cylinder R², having a piston R and valve R³ and connected to the sucker-bar tubes 30 by a flexible hose S and pipe S', which communicate by suitable channels S³, Fig. 4^c, with all the sucker-tubes, each one of which is provided with a valve 41, arranged to cut off the suction should there be no letter in the supply-compartment. The ascent of the piston R produces a vacuum in the sucker-tubes 30 when they are brought in contact with the letters, and this vacuum is maintained while the sucker-tubes are transferring the letters

and is destroyed at the moment the transferring device reaches the point to drop the letters by the reverse stroke of the piston R, 70 which opens the valve 41 to admit the air.

The working of the machine is expeditious and is equally effective in handling long, short, and thick and thin letters without adjustment, and one person can supply a machine having six letter-supplying compartments. 75

As the pressure of the sucker-tubes upon the letters has been found to give the package an outward movement upon the follower, 80 I provide the surface with rubber strips 10', placed in oblique relation, so as to form holds for the bottom letter of the package, and thus prevent it from slipping or moving out. (Shown in Fig. 10.) 85

Having thus described a structure embodying in preferred form all the several features of my invention in combination, what I claim, and desire to secure by Letters Patent, is—

1. In a postmarking and stamp-canceling machine, the combination, with a suitable yielding impressing-stamp and an intermittently-operating endless apron, a rock-shaft mounted in the stamp-shank, having a crank-arm on each end, and a yielding plunger-rod 90 connected to one of said crank-arms, for operation substantially as described.

2. In a postmarking and stamp-canceling machine, the combination, with a suitable yielding impressing-stamp and an intermittently-operating endless apron, a rock-shaft mounted in the stamp-shank, having a crank-arm on each end at about right angles to each other, one of said crank-arms having a slot, and a yielding plunger-rod connected by a pin 100 in the said slot, one of said crank-arms and the plunger-rod having a length sufficient to extend below the impressing-surface, for operation substantially as described.

3. In a postmarking and stamp-canceling machine, the combination, with an impressing-stamp, a carrying-box therefor, and a spring upon said stamp, and an intermittently-operating endless apron, a rock-shaft mounted in the stamp-shank, having a crank-arm on each end, a plunger-rod connected to one of said crank-arms, a tube or barrel containing said plunger-rod, and a spring within said barrel upon said plunger-rod, for operation substantially as described. 115

4. In a postmarking and stamp-canceling device, a stamp having a spring-sustained shank part C, provided with a slotted impressing-head and a vertical side dovetail rib y, in combination with the horizontal stud or hub I, having an end recess y² for engaging said shank-rib, an armed type-wheel upon said stud or hub, and a screw centrally engaging said stud against said shank-rib, substantially as described. 125

5. In a postmarking and canceling stamp, a stamping device having a spring-sustained impressing part, the head A whereof has two parallel slots, one of which is of dovetail cross-

section, type *n* of corresponding form to said slot seated therein and having inclined holes in their blank ends, in combination with an armed type-wheel arranged to operate within the other slot of said head, whereby the type for the month and the day may be easily and quickly changed in said head.

5 6. In a postmarking and stamp-canceling machine, the combination, with a suitable to yielding impressing-stamp, of a rock-shaft mounted in the stamp-shank, having a crank-arm on each end, a plunger-rod connected to one of said crank-arms, and an intermittently-operating endless apron having an opening 15 registering with said plunger-rod, for operation in the way described.

7. In a postmarking and stamp-canceling machine, a stamping device consisting of a horizontal cross-bar having a series of vertically-yielding impressing-stamps, each containing a horizontal rock-shaft having a crank-arm on each end, and a yielding plunger-rod connected to each one of said crank-arms, intermittently-operating endless aprons corresponding with said stamps and having openings registering with said plunger-rods, letter-supplying compartments registering with said aprons and stamps, an intermittently-operating pneumatic letter-transferring device, and 25 suitable mechanism for operating the stamp-carrying bar in unison with the movements of the aprons and of the said transferring device, for operation substantially as described.

8. In a postmarking and stamp-canceling machine, the combination, with a suitable yielding impressing-stamp and an intermittently-operating endless apron, a horizontal rock-shaft mounted in bearings in the stamp-shank, having a crank-arm carried in relation 40 to said apron to be brought into contact therewith by the descent of the stamp to shunt the latter out of action when descending, in the way and for the purpose described.

9. In a machine for postmarking mail-matter and canceling the postage-stamps thereon, the combination of intermittently-operating endless aprons, a series of letter-supply compartments, and an intermittently-operated letter-transferring device, with a horizontal 45 cross-bar having vertically-depending impressing-stamps, vertical slides connecting

the ends of said bar with the end frames, a rock-shaft having slotted arms connecting said slides, and suitable mechanism for operating said rock-shaft, substantially as described. 55

10. In a postmarking and stamp-canceling machine, the combination of intermittently-operating endless aprons, a series of letter-supplying compartments, and an intermittently-operated letter-transferring device, 60 with a horizontal cross-bar having vertically-depending impressing stamps, vertical slides connecting said bar with the end frames, a rock-shaft having slotted arms connecting said slides, a spring-sustained inking-roll, 55 horizontal riders or bearers for guiding the inking-roll under the stamps, and suitable mechanism for operating said inking-roll and the stamp-carrying bar, substantially as described. 70

11. In a postmarking and stamp-canceling machine, the combination of intermittently-operating endless aprons, a series of letter-supplying compartments, and an intermittently-operated letter-transferring device, 75 with a vertically-operated stamp-carrying bar having vertical end slides and horizontal riders or bearers registering with horizontal riders or bearers having fixed relation to the end frames, a spring-sustained inking-roll 80 adapted to move horizontally under said riders when in registering relation, and mechanism for operating said inking-roll and the said stamp-carrying bar, substantially as described. 85

12. In a postmarking and stamp-canceling machine, the combination of intermittently-operating endless aprons and intermittently-operating letter-transferring devices having a circular movement over said aprons, a vertically-reciprocating stamp-carrier, a horizontally-reciprocating inking-roll, coacting fixed and movable rider parts for said roll, and suitable automatically-operated mechanism for conjointly operating them in the way described. 90 95

In testimony whereof I affix my signature in presence of two witnesses.
